US00D498788S

(12) United States Design Patent (10) Patent No.: **US D498,788 S**
Lubking (45) Date of Patent: **** Nov. 23, 2004**

(54) DATA CARD

(75) Inventor: **Colleen C. Lubking**, Richmond, VA (US)

(73) Assignee: **Capital One Financial Corporation**, Falls Church, VA (US)

(**) Term: **14 Years**

(21) Appl. No.: **29/179,079**

(22) Filed: **Apr. 3, 2003**

(51) LOC (7) Cl. **19-08**

(52) U.S. Cl. **D19/10**

(58) Field of Search **D14/435, 436, D14/437, 438; D19/9, 10, 11, 12; D20/40; 40/1.5, 625; 235/380, 382, 435, 436, 449, 454, 468, 469, 488, 491, 492, 493; 283/70, 72, 74, 75, 82, 99, 107, 904; 428/916; 360/2**

(57) CLAIM

The ornamental design for a data card, as shown and described.

DESCRIPTION

FIG. 1 illustrates a perspective view of a data card, showing my new design;

FIG. 2 illustrates a front plan view thereof;

FIG. 3 illustrates a rear plan view thereof;

FIG. 4 illustrates a bottom elevational view thereof;

FIG. 5 illustrates a top elevational view thereof;

FIG. 6 illustrates a left side elevational view thereof;

FIG. 7 illustrates a right side elevational view thereof;

FIG. 8 illustrates an exploded plan view thereof;

FIG. 9 illustrates a perspective view of a data card, showing my new design;

FIG. 10 illustrates a front plan view thereof;
FIG. 11 illustrates a rear plan view thereof;
FIG. 12 illustrates a bottom elevational view thereof;
FIG. 13 illustrates a top elevational view thereof;
FIG. 14 illustrates a left side elevational view thereof;
FIG. 15 illustrates a right side elevational view thereof;
FIG. 16 illustrates an exploded plan view thereof;
FIG. 17 illustrates a perspective view of a data card, showing my new design;
FIG. 18 illustrates a front plan view thereof;
FIG. 19 illustrates a rear plan view thereof;
FIG. 20 illustrates a bottom elevational view thereof;
FIG. 21 illustrates a top elevational view thereof;
FIG. 22 illustrates a left side elevational view thereof;
FIG. 23 illustrates a right side elevational view thereof;
FIG. 24 illustrates an exploded plan view thereof;
FIG. 25 illustrates a perspective view of a data card, showing my new design;
FIG. 26 illustrates a front plan view thereof;
FIG. 27 illustrates a rear plan view thereof;
FIG. 28 illustrates a bottom elevational view thereof;
FIG. 29 illustrates a top elevational view thereof;
FIG. 30 illustrates a left side elevational view thereof;
FIG. 31 illustrates a right side elevational view thereof;
FIG. 32 illustrates an exploded plan view thereof;
FIG. 33 illustrates a perspective view of a data card, showing my new design;
FIG. 34 illustrates a front plan view thereof;
FIG. 35 illustrates a rear plan view thereof;
FIG. 36 illustrates a bottom elevational view thereof;
FIG. 37 illustrates a top elevational view thereof;
FIG. 38 illustrates a left side elevational view thereof;
FIG. 39 illustrates a right side elevational view thereof;
FIG. 40 illustrates an exploded plan view thereof;
FIG. 41 illustrates a perspective view of a data card, showing my new design;
FIG. 42 illustrates a front plan view thereof;
FIG. 43 illustrates a rear plan view thereof;
FIG. 44 illustrates a bottom elevational view thereof;
FIG. 45 illustrates a top elevational view thereof;
FIG. 46 illustrates a left side elevational view thereof;
FIG. 47 illustrates a right side elevational view thereof; and,
FIG. 48 illustrates an exploded plan view thereof; The broken lines in the figures have been shown for illustration purposes only and form no part of the claimed invention.
